(57) **CLAIM**

We claim, the ornamental design for a combined ear phone and mobile apparatus, as shown and described.

DESCRIPTION

FIG. 1 is a top and front perspective view of the ear phone of the combined ear phone and mobile apparatus showing our new design; the ear phone is shown separately for purposes of illustration;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof;

FIG. 7 is a bottom elevational view thereof;

FIG. 8 is a front perspective view thereof, showing the combined ear phone and mobile apparatus in an alternate position; and,

FIG. 9 is a front elevational view of the combined ear phone and mobile apparatus with the cord drawn broken away for indeterminate length; the undisclosed rear is not part of the claimed design.
